PROTECTIVE DEVICE

Francis H. Montmarquet, Little Falls, N. J.

Application May 1, 1939, Serial No. 270,965

2 Claims. (Cl. 128—138)

This invention relates generally to protective devices intended to support and protect the abdominal parts of athletes and other persons. More particularly it relates to protective devices comprising a relatively rigid hollow protecting member, and means for holding said member in place on the abdomen.

While devices of this character have been and now are in common use, all of them that I am familiar with, because of their many shortcomings fail to attain the optimum of effectiveness.

The materials used for the relatively rigid protecting member, which is usually in the form of a shell-shaped cup have heretofore, to my knowledge, been of a character such that when subjected to force they will either be permanently deformed or be shattered, or will retain their form and transmit the force to the abdominal portions with which they are in contact.

In the first case, once such deformation has begun, resistance to further deformation is usually destroyed, and with it protective utility; on the contrary the protective cup may become dangerous because the deformed portions may be of such conformation that when forced against and into the body of the wearer they may seriously injure him. As an example of materials that will behave in this manner may be mentioned sheet metals that lend themselves to forming operations by stamping or drawing. Sheet aluminum belongs in this category.

Bakelite is an example of the class of materials that may be shattered. These materials are apt to crush and break into fragments which may be caused to forcibly enter the flesh of the wearer and inflict frightful injuries.

Tough cast metals are an example of that class of materials that cannot be deformed and that will transmit force directly to the body. If the force is sufficiently great such materials may cut into the flesh of the wearer.

A further disadvantage that is met with is that such protecting cups require elaborate means for holding them against displacement, because their surface portions are so devoid of frictional resistance, that friction is not sufficient to prevent their shifting. Where these cups are not permanently united to the supporting structure, closed pouches or pockets have been resorted to. All of these added complexities increase the cost of such devices and the inconvenience of wearing them.

Where the protecting cup is made of metal a sensation of discomfort is often experienced be-

cause of the relatively high thermal conductivity of metals, and where the cup is of drawn or stamped sheet metal, there is often a lack of adequate depth to its contours because of the limitations of the drawing and stamping processes as applied to sheet metals.

It is the general object of my invention to provide a protective device that is simple, effective and low in cost.

10 It is further among the objects of my invention to provide a protective cup made of a material that is resistant but at the same time yieldable and also resilient so that it will resume its shape after ordinary deformation, and further a material that is a poor conductor of heat, and will have sufficient frictional resistance to resist displacement.

To attain these objects and such further objects as may appear herein or be hereinafter pointed out, I make reference to the accompanying drawing, forming a part hereof, in which:

20 Figure 1 is a perspective view of an athletic supporting belt having a protective cup positioned therein and illustrating one embodiment of my invention, portions of the facing being shown broken away to disclose the location of the cup;

25 Figure 2 is a sectional view substantially on the line 2—2 of Figure 1, looking in the direction of the arrows;

30 Figure 3 is a transverse sectional view, substantially on the line 3—3 of Figure 1, looking in the direction of the arrows, of a protective cup;

35 Figure 4 is a section, on an enlarged scale, through a piece of material suitable for use in my improved protective cup;

40 Figure 5 is a fragmentary sectional view similar to Figure 2 of a modified form of supporting belt with a protective cup positioned therein;

In Figures 1, 2 and 3 I have shown a protective cup A positioned within a pocket provided on an athletic supporting belt B. The latter may 45 comprise a belt or waist-band portion 10 to which are suitably secured, as by stitching 13 and 14, the ends of leg bands 11 and 12 that cross each other at their crotch-engaging portions.

50 The pocket 15 comprises a body engaging fabric portion 16, secured in any suitable or preferred manner to the waistband and to the leg bands where they cross each other. Such securing means may consist of stitching 17 joining the portion 16 to the waistband 10, and stitching

(not shown), joining the lower end of the piece 16 to the leg bands 11 and 12.

The pocket 15 further comprises a piece 18 suitably secured, as by stitching 19, to the piece 16, which in the drawing is shown as extending partly around the piece 18, so as to leave the pieces 18 and 16 unsecured at the top, whereby a pocket is formed into which the cup A may be inserted from above.

The waistband 10 is preferably, although not necessarily, elastic, and the leg bands 11 and 12 may also be of elastic material, if desired. The pieces 16 and 18, in view of their function in properly positioning the cup A are preferably non-elastic, and for purposes of ventilation may be of coarse mesh fabric, which has the additional advantage of holding the cup A in place by friction and preventing its lateral shifting.

It is to be noted that I have provided no closure means for the pocket, because I have found that while such means or equivalent is almost indispensable for cups of the types used heretofore, it is not necessary where my improved protective cup is used.

The protective cup A is arched in both longitudinal and transverse section, as appears from Figures 2 and 3, and is shaped so as to conform to the body portions to be protected.

The preferred embodiment of the protective cup may be described as of generally inverted triangular contour with the upper or base portion shallow, and the cup increasing in depth towards its lower or apex portions. The rim portions of the cup are turned outward and inward so as to form a bead or a bead-like flange 20 which serves to make the cup more form-retaining and increases its resistance to displacement from its position in the pouch or pocket 15. By forming this flange on a large radius, as shown, danger of cutting into the flesh is also reduced.

Shallow ribs 21 may also be provided for similar purposes, that is to stiffen the device to retain its form and to increase its resistance to shifting.

In Figure 4 I have shown in section, on an enlarged scale, one type of material, which I have found suitable for my protective cup in order to impart to it all of the novel and desirable properties enumerated hereinabove. In this figure five layers of fabric 25 are indicated in superposed relation and surrounding them and impregnating them is indicated a body of material 26 that is resilient and form-retaining under ordinary conditions of use, but that may be rendered plastic for purposes of manufacture when exposed to abnormal conditions of moisture, a solvent or plasticizers for the binder with or without temperature, pressure or other factors alone or in combination.

Among such impregnating substances may be mentioned by way of example the modern thermoplastic synthetic plastics; also heat setting and hardening phenol aldehyde plastics or the older glue sizing which may be waterproofed, tanned or otherwise insolubilized.

The fabric is preferably coarse in texture so as to provide sufficient body and to provide rough exterior surfaces that, when contacting with the fabric of the belt B, will frictionally resist displacement relatively thereto, particularly when the parts are under stresses such as pressure or tension.

It will be understood, of course, that the showing of five plies of fabric in Figure 4 is illustrative merely, and that any number of plies may

be used, depending on the characteristics of the particular fabric and the particular impregnating material used. Also knitted fabric may be employed as the fabric reinforcing ply or as a number of plies thereof, or in combination with the woven fabric, to obtain combination plies.

In the process of manufacture the material may be first blanked, then subjected to the appropriate preparatory treatment, such as heating or steeping in water or appropriate solvent or plasticizer, or both, after which it may be formed in suitable dies or molds. It is then allowed to cool or dry, or both. After the final operations, which may include trimming, a protective coating may be applied, as by dipping or otherwise, which is preferably waterproof, heat-resistant and chemically inert. As an example of such a coating I may mention Bakelite varnish. When so coated the cup may be washed when desired without deterioration thereof.

In Figure 5 I have shown a cup A mounted in a belt B' that is similar to the belt B of Figures 1 and 2, in that it has a waistband portion 10', leg portions 11' and 12' and a fabric portion 16'. However, since there is nothing corresponding to the piece 18, there is no pocket into which the cup A may be received. I have found that such a pocket is not necessary to the proper functioning of my cup, since its properties of yielding under pressure and its frictional resistance to displacement make it effective when it is placed under the piece 16, and between the same and the skin of the wearer.

It will therefore appear from the foregoing illustrative disclosure that by the novel use of the materials herein described that I have been able greatly to increase the effectiveness of protective devices of this character by imparting to them heretofore unknown characteristics.

It will also appear that the resiliency of the composite employed by me makes it possible to use my device in direct contact with the body without cumbersome expedients to protect the edge which have previously been found necessary as by a beading of rubber or edging of cloth.

By my device the bead or flange 20 is of non-frangible and resilient character offering a wide non-chafing, non-cutting edge which dispenses with the need for the more cumbersome and expensive edging expedients heretofore employed. Thus, stiffening action is obtained at the periphery without loss of adequate protection and comfortable resiliency.

By my device economy is effected in production with the unexpected resiliency, non-frangible and non-splitting character of the material, permitting exposure to the intended uses free from the hazard or discomfort experienced with the devices made previous to mine.

Thus the nature of the materials and the contour of the devices lends itself admirably to the production of the protective cup having properties heretofore not achieved.

Having thus described my invention, and illustrated its use, what I claim as new and desire to secure by Letters Patent is:

1. An athlete's supporter and protector, made of a composite material comprising several plies of fabric and a suitable resinous substance as a stiffening agent, the protector having a main body portion arched in longitudinal and transverse sections and shaped to receive the body part being protected, the edge of said main body portion being turned outwardly and reversely and forming an endless trough-shaped border integral and

continuous with the main body portion and of the same composite material.

2. An athlete's supporter and protector, made of a composite material comprising several plies of fabric and a resinous or other suitable substance as a stiffening agent impregnating said fabric, the protector having a main body portion arched in longitudinal and transverse sections

5 and shaped to receive the body part being protected, the edge of said main body portion being turned outwardly and reversely and forming an endless trough-shaped border integral and continuous with the main body portion and of the same composite material.

FRANCIS H. MONTMARQUET.
